[57] CLAIM

The ornamental design for an ice cream station, as shown.

DESCRIPTION

FIG. 1 is a front elevational view of an ice cream station showing my new design;

FIG. 2 is a rear elevational view thereof;

FIG. 3 is a top plan view thereof;

FIG. 4 is a right side elevational view thereof;

FIG. 5 is a left side elevational view thereof;

FIG. 6 is a cross-sectional view taken along line 6—6 of FIG. 1.
